PULSE MODULATOR

Howard R. Hegbar, Princeton, N. J., assignor to
 Radio Corporation of America, a corporation
 of Delaware

Application June 29, 1943, Serial No. 492,761

2 Claims. (Cl. 250—27)

1

My invention relates to the production of electrical pulses and particularly to systems wherein stored energy is to be discharged through a plurality of parallel connected electric discharge devices such as gas or vapor tubes.

When two or more tubes of the Thyratron type or the like are operated in parallel, there usually is difficulty in obtaining simultaneous ignition. If the paralleled tubes do not have identical grid control characteristics and are triggered with a grid voltage having a finite slope on the leading edge, one tube will fire and thus reduce the plate voltage on the other, which will either fire late or will not fire at all during the cycle.

An object of the present invention is to provide an improved method of and means for obtaining a simultaneous discharge through a plurality of parallel connected electric discharge tubes.

Another object of the invention is to provide an improved method of and means for obtaining simultaneous ignition of parallel connected gas or vapor tubes.

A further object of the invention is to provide an improved method of and means for producing high voltage electrical pulses in response to the occurrence of control or triggering pulses.

The invention will be described particularly with respect to the modulation of high frequency oscillators such as magnetrons which, in pulse-echo apparatus, require large peak power at a small duty cycle. In many applications, particularly in lightweight pulse-echo apparatus, it is desirable that the modulator be operated from a low voltage power supply. In such a modulator a wave-forming electrical network may be discharged through a gas or vapor tube, and the resulting pulse may be put through a pulse transformer to obtain the desired output voltage. When the required peak power output of the modulator exceeds the electrical capability of the gas or vapor tube, either a larger tube must be selected or a means must be provided for parallel operation of two or more tubes.

In accordance with my invention, the desired parallel operation may be obtained by utilizing two circuit actions either alone or in combination, the latter being preferable. One action is that of regeneration or mutual ignition wherein the ignition of any tube or tubes immediately causes an increase in second-grid voltage of the unfired tube or tubes. To aid this regeneration, the second action may be introduced which consists of maintaining the anode voltage of the unfired tube or tubes at a value many times the magni-

5 tude of the static discharge voltage. This second action is not obtained when tube anodes and cathodes are directly connected, because then the ignition of one tube will cause the anode-cathode voltage of the rest to fall to the low discharge voltage.

The invention will be better understood from the following description taken in connection with the accompanying drawing in which

10 Figure 1 is a circuit diagram illustrating an embodiment of the invention wherein the feature of cross-connection for mutual ignition is used alone.

15 Figure 2 is a circuit diagram of another embodiment of the invention wherein there is added to the cross-connection feature means for maintaining the anode voltages at values high enough to facilitate ignition of the parallel connected tubes.

20 Figures 3 and 4 are circuit diagrams of embodiments of the invention wherein three and four tubes, respectively, are cross-connected to obtain simultaneous ignition, and

25 Figure 5 is a circuit diagram of an embodiment of the invention where a bias is applied to the control grids of the tubes.

In the several figures, similar parts are indicated by similar reference characters.

Fig. 1 shows an embodiment of the invention comprising a wave-forming network 10 which may be in the form of a low pass filter having series inductance coils 11 and shunt capacitors 12. The capacitors 12 are charged to a high potential from a direct current source 13 which is connected to the network 10 through a choke coil 14. The choke coil 14 has such high impedance at the pulse frequency that this end of the network 10 looks into substantially an open circuit.

30 It is well known that a rectangular voltage pulse may be obtained by discharging certain types of networks such as the network 10 through a load having an impedance substantially equal to the characteristic impedance of the network. In Fig. 1, the network 10 is discharged periodically through a pair of parallel connected vapor tubes 16 and 17 (which, in the example assumed, are Thyratrons type 2050) and through the primary 18 of a transformer 19 coupled to the load

35 to produce the voltage pulses 15. The load in this instance is a magnetron 21 which is to be keyed by the applied pulses for the production and transmission of pulses of high frequency radio energy. The secondary of the transformer 50 19 may be a bifilar winding consisting of two

coils 20 and 20a through which heating current is supplied to the filament of the magnetron from a filament heating transformer 25.

The tubes 16 and 17 each have a cathode, an anode, a control grid and a screen grid. The anodes are directly connected to each other but the cathodes are connected to each other through low impedance elements 22 and 23 in the cathode leads of the tubes 16 and 17, respectively. The elements 22 and 23 preferably are inductors but may be resistors. In the example shown, the inductance coils 22 and 23 each had an inductance of about 0.5 microhenry, the resistance of the coils being of the order of $\frac{1}{100}$ ohm.

The tubes 16 and 17 are rendered conducting periodically by applying to their control grids periodically recurring trigger pulses 24 which are supplied from a suitable pulse generator 26. In the specific example being described, the pulses 24 and the output pulses 15 have a repetition rate of 1000 per second. The pulses 15 have a duration of 2 microseconds. The pulses 24 may be applied through a coupling capacitor 27 and through grid-current limiting resistors 28 and 29. Simultaneous ignition of the tubes 16 and 17 is obtained by connecting the cathode of tube 16 to the screen grid of the tube 17 through a connection 31 and by connecting the cathode of the tube 17 to the screen grid of the tube 16 through a connection 32. It will be apparent that as soon as one of the tubes ignites the resulting voltage drop in the impedance element in its cathode lead will drive the screen grid of the other tube more positive and immediately cause it to ignite also.

It may be noted that in practice it is preferred to tune the choke coil 14 and the capacitors 12 of the network 10 to resonate at $\frac{1}{2}$ the repetition frequency of the pulses for the purpose of obtaining double the power supply voltage on the network 10 at the time it is discharged.

Referring to Fig. 2, I have shown the use of two wave-forming networks 36 and 37 which are discharged by the tubes 16 and 17, respectively, both networks being discharged through the primary 18 of the load transformer 19. This provides the second action previously mentioned, namely, that of maintaining the anode of an unfired tube at a comparatively high voltage after another tube has ignited. In addition, it is preferred to utilize the cross-connection 31 and 32 as previously described. The cathode impedance elements may be resistors, as indicated at 22a and 23a, if desired.

The advantage in using two networks as shown in Fig. 2 will be evident from the following considerations. Taking specific values, by way of example, assume each of the networks 36 and 37 has a characteristic impedance of 33 ohms. Since these network impedances are in parallel with each other when the tubes 16 and 17 ignite, the load impedance should be $\frac{1}{2} = 16.5$ ohms. We may now determine what the voltage on the anode of tube 17 will be if only the tube 16 ignites.

Let E_0 be the voltage to which each of the networks 36 and 37 is charged. Then the current through the load when only tube 16 ignites will be

$$\frac{E_0}{33+16.5}$$

and the drop across the load will be

$$\frac{E_0}{33+16.5} \times 16.5 \text{ ohms} = \frac{1}{2} E_0$$

The voltage on the anode of tube 17 then will be $E_0 - \frac{1}{2} E_0 = \frac{1}{2} E_0$. This is a much higher voltage than for the corresponding case when the circuit of Fig. 1 is employed. Because of this, there is less difficulty in making the tubes 16 and 17 ignite practically simultaneously.

In Fig. 3 the regenerative or cross-connection feature is shown applied to three vapor tubes 16, 17 and 41 connected in parallel. The cathode lead of the tube 41 includes an impedance element 42. A grid-current limiting resistor is indicated at 43. Only one wave shaping network 10 is illustrated but separate networks for the several vapor tubes may be employed as illustrated in Fig. 2. In order that the ignition of any one tube will apply a positive voltage to the screen grid of all the other tubes, the screen grids of the tubes 16, 17 and 41 are connected to the center points of three potentiometers 46, 47 and 48, respectively, through conductors 49, 51 and 52, respectively. Each potentiometer consists of two resistors in the example illustrated, and is connected between the cathodes of the two tubes other than the one having its screen grid connected thereto. For instance, potentiometer 48 is connected between the cathodes of tubes 16 and 17, and the connection 52 from its midpoint goes to the screen grid of tube 41.

In Fig. 4 the same regenerative principle is shown applied to a still larger number of parallel connected tubes. Here there are four tubes 16, 17, 41 and 53 in parallel. The cathode lead impedance element and the grid-current limiting resistor for the tube 53 are indicated by reference characters 54 and 56, respectively. The method of connecting the screen grids to potentiometers is the same as described for Fig. 3, but where there are four tubes each potentiometer consists of three resistors, two of the resistors being connected to the cathodes of two tubes as before and the third resistor being connected from the potentiometer midpoint to the cathode of a third tube. Also, as in Fig. 3, the potentiometer midpoint is connected to the screen grid of the remaining tube.

For example, one potentiometer is indicated at 57 and comprises resistors 57a, 57b and 57c. The resistors 57a and 57b are connected between the cathodes of tubes 16 and 17, while the resistor 57c is connected between the midpoint of resistors 57a-57b and the cathode of the tube 41. The midpoint of potentiometer 57 is connected through a conductor 58 to the screen grid of the remaining tube 53. If any one of the tubes 16, 17 and 41 ignites before the tube 53 ignites, the midpoint of potentiometer 57 will go positive and apply a positive potential to the screen grid of tube 53 so that it will ignite immediately.

The other three-resistor potentiometers 61, 62 and 63 are connected in a similar manner to the tube cathodes and to the screen grids whereby the screen grid of any tube will go more positive in response to the ignition of any other tube. Thus the four tubes will ignite substantially simultaneously in response to the application of a triggering pulse.

Fig. 5 shows a cross-connected circuit similar to that of Figs. 1 and 2 wherein the cross-connections include capacitors 71 and 72 so that a bias voltage may be applied to the screen grids through resistors 73 and 74. This bias voltage may be of negative polarity, for example, to aid in deionization, or a different bias voltage may be applied for some other purpose.

I claim as my invention:

1. In combination a plurality of electric discharge tubes of the gas or vapor type, each tube having a cathode, an anode, a control grid and an auxiliary grid, a plurality of impedance elements connected between ground and said cathodes, respectively, a plurality of wave-forming networks, means for connecting said anodes to said networks, respectively, voltage supply means for said networks, a load connected in series with 10 said tubes and said networks, means for applying a voltage appearing at the cathode end of any one of said impedance elements to the auxiliary grids of the other tubes, and means for applying a triggering voltage to said control grids.

2. In combination in a pulse producing circuit, a plurality of electric discharge tubes of the gas or vapor type, each tube having a cathode, an anode and a grid electrode, a plurality of impedance elements connected between a common point 20 and said cathodes, respectively, a plurality of

15

wave-forming networks, means for connecting said anodes to said networks, respectively, voltage supply means for said networks, a load connected in series with said tubes and said networks, means for triggering said discharge tubes at a certain repetition rate, and means for applying a voltage appearing at the cathode end of any one of said impedance elements to the grid electrodes of the other tubes.
